ROTARY DISCONNECT SWITCH

Peder B. Hoye, Maywood, Ill., assignor to Electrical Engineers Equipment Co., Melrose Park, Ill., a corporation of Illinois

Application August 10, 1942, Serial No. 454,235

5 Claims. (Cl. 200—6)

The present invention relates generally to high voltage electric disconnect switches of the enclosed type, and more particularly to such enclosed disconnect switches wherein the circuit is opened or closed by rotary motion of the contacts. According to the preferred form of my invention the switch contacts, both stationary and movable, are housed in a vitreous housing which is preferably made of glass or wet process porcelain.

One of the principal objects of my present invention is to provide a compact, efficient switch for either indoor or out-of-doors use which is easy to construct and economical to manufacture. Compactness is obtained by having rotating contacts for opening or closing the circuit which contacts do not require the space necessarily used by contacts having a rectilinear motion. Fewer parts add to the compactness of the switch and contribute to lower costs of construction and operation.

Another object of my invention is to provide switch units that are readily mounted on the sides, top or ends of cross arms of power-line carriers, whichever is more desirable or convenient. Such mounting is not readily or practically attainable by switches which require mounting on a vertical panel and which have rectilinear motion.

A further object is to provide novel rotary contacts of the prestressed spring type. The bearing of these prestressed contacts may be either radial or axial and the type of engagement may be either of the surface type or of the point or high pressure type.

It is understood that any number of these units may be mounted side by side and operated by a common crank arm, or other control. In fact, this is one of the advantages of my invention.

A still further object of the present invention is the provision of substantially completely weatherproof units whose interiors optionally are visible without opening of the housing and are readily accessible for any repair work. These units have readily detachable cover plates of glass, transparent plastic or other transparent material. If preferred, however, covers of opaque materials may be used instead. An insulating liquid such as oil may cover the engaging contacts to assist in interruption of current flow.

A further advantage of these switches is their 55

adaptability to use with high voltages with a high factor of safety.

These and other features and advantages will be more fully understood and appreciated upon reference to the following detailed description taken in connection with the accompanying drawings wherein specific embodiments of my invention are disclosed.

In the drawings:

10 Figure 1 shows a set of three rotary disconnect switches with vertical axes on a cross arm of a pole which switches are all linked together and are gang operated by one bell crank;

15 Figure 2 shows another set of three rotary disconnect switches with horizontal axes on the cross arm of a pole, which switches are gang operated;

20 Figure 3 is a vertical longitudinal section taken along the line 3—3 of Figure 4 of a rotary disconnect switch with a vertical axis adapted, for example, to be mounted on the side (as in Figure 1) or end of a cross arm;

25 Figure 4 is a bottom view of the rotary switch of Figure 3 with a portion of the screen broken away to show the interior;

30 Figure 5 is a front elevation, with portions broken away, of a rotary disconnect switch with a horizontal axis adapted, for example, to be placed on the side (as in Figure 2) or top of a cross arm;

35 Figure 6 is a vertical cross sectional view of the rotary switch of Figure 5 along the lines 6—6 of Figure 5;

35 Figure 7 is a horizontal cross sectional view of the rotary switch shown in Figure 5 along the lines 7—7 of Figure 6;

40 Figure 8 is a front elevation, with portions broken away, of another style of rotary disconnect switch and indicates the manner of connecting the switches together on a single operating axle;

45 Figure 9 is a vertical cross sectional view of the form of rotary switches shown in Figure 8 (the section being taken substantially on the line 9—9 of Figure 8);

50 Figure 10 is a front elevation, partially in section and with the cover plate removed, of a fourth style of rotary disconnect switch;

50 Figure 11 is a cross sectional view of the rotary switch of Figure 10 along the lines 11—11 of Figure 10;

Figure 12 shows a detail view of the front of the cover locking engagement shown in the side view in Figure 11; and

Figure 13 is a fragmentary sectional view of a modified form of contact such as may be employed in the device of Figures 8 to 12.

Referring first to Figures 3 and 4 showing the rotary disconnect switch 8, there is provided a two part housing of vitreous insulation preferably of glass or wet-process porcelain surrounding and covering the live portions of the switch. The upper of the two parts of the housing is in the form of a cap 10 which rests on the upper surface 11 of the lower portion of the rotary switch 8 which lower portion 12 is substantially barrel shaped or cylindrical. The cap 10 is fastened to the barrel 12 by means of bolts such as bolts 14, the heads 15 of which abut against the bottom of the annular support 19 of the metallic bracket 20 and the shanks of which pass through holes in the support 19 and holes in the shoulders 17 of the barrel 12. These bolts 14 are threaded into pre-threaded metal inserts 21 which are cemented inside hollow bosses 23 which are integral parts of the cap 10. In this way the cap 10 is joined to the barrel 12 and the two parts of the housing are firmly secured to the metal bracket 20.

The bracket 20 comprises two legs 24, 24 formed integrally with the annular support member 19 for bearing the housing 8, which support member 19 has four cross arms 25 which brace the support 19 and at their junction carry an integral barrel 27 which contains a bronze or other antifriction metal bearing sleeve 28. This sleeve 28 bears an axle 30 which has an enlarged end 31 which is cemented into a cavity within the insulator 33 and which bears and turns on the collar 32 of the barrel 27. Cemented within a second (and upper) cavity in the insulator 33 is a cylindrical metal stub 34 to which is secured by screws 35, 35 the laminated switch blade 37. On the lower end of the axle 30 is secured crank arm 38 for turning the axle and consequently shifting the position of the switch blade 37.

The switch blade 37 of the illustrated device is formed of four metal strips which are clamped together by cap screws 35, 35. The upper two strips are copper and the lower two are of phosphorus bronze which act as leaf springs and thus produce firm electrical contact between the copper of the switch blade 37 and the two stationary contacts 39, 39. The contact may be flat surface contact or it may be high pressure point contact. It will be noted that the stationary contacts have beveled edges as at 36 so that the switch blade is directed downwardly as it comes into engagement with the contacts 39. This downward thrust deforms the blade 37 and permits the phosphorus-bronze leaf-springs to strongly force the upper surface of the blade against the contacts 39.

The stationary contacts 39, 39 each have shanks 40 which pass through holes in the shoulder 17 of the barrel 12 and also through holes in the split binding post blocks 41, 41. The wires or cables 42 carrying the electric power pass into the interior of the housing of the switch 8 through ports 43 in the side of the housing cap 10. Then the wires 42 are inserted in the binding post blocks 41 and a nut 44 is threaded on to the end of the shank 40 of each stationary contact 39 so that the split binding post blocks will be squeezed and will tightly engage the ends of the wires. The shanks 40 of contacts 39 may be cemented in permanent position.

The porcelain or glass housing does not rest directly on the annular metal support 19 but in-

stead sits on an annular cup 47 of more or less yielding insulating material such as cork or compressible fiber. Between the support 19 and the insulating cup 47 is positioned a bronze screen 48 which fits snugly about the collar 32 of the barrel 27 and which separates the interior of the housing from the open air. This screen 48 is primarily used to keep out dirt and insects which otherwise might get in and foul the surfaces of the stationary contacts 39 and the revolvable switch blade 37.

As shown in Figures 3 and 4, the switch blade 37 is in engagement with the stationary contacts 39 so that there is a current flow through the rotary disconnect switch from one wire to another. But now if the handle 38 is rotated 90° the switch blade will be rotated 90°, become disengaged from the stationary contacts and lie in a direction parallel to the length of these contacts. In the construction of the switch, the size of the instrument is such that there will be a certain minimum distance between the stationary contacts 39. This minimum distance will depend upon voltage requirements. The screen 48 or bolts 15 may be connected to ground as an additional precaution against arcing due to severe over-voltages.

The bracket 20 has holes 22, 22 in each leg 24 through which screws may be inserted for mounting the rotary switch. With the construction shown the switch could be mounted on the side or end of a cross bar or on the side of a post with equal ease. Mounted on the side of a cross arm, for example, several of these units may be linked together by rods joining the handles 38 together. A hole 46 in the end of the arm 38 permits such linking so that a set of several switches may be activated by one crank. See crank 49, for example, in Figure 1. The operating cranks and the brackets 20 are preferably grounded. An advantage of the construction of Figures 3 and 4 is that a lineman may safely stand upon the cover 10.

Figures 5, 6 and 7 are the several views of another style of rotary disconnect switch. Though the form is different the principle is the same, namely, an enclosed disconnecting switch with a double ended rotatable blade. It is necessary to have the contact elements separated a certain minimum distance (the distance depending on the voltage to be sustained) when the switch is in open position. I have discovered that the rotatable switch blade pivoted at its center is the economical and space saving means for accomplishing this end. That feature is common to all the devices illustrated in Figures 1 through 13.

In Figure 5 the housing 50 is also preferably of wet process porcelain or glass and has a glass or moulded insulating cover 51 bolted on the front side by bolts 53, 53 which permits a view of the interior without the necessity of opening the housing. In the prior device of Figures 3 and 4 a view of the interior is possible through the bronze screen 48 in the bottom of the unit or to some degree through the housing if made of glass.

The binding posts or terminals 54, 54 which may be bonded in place have at their inner ends the stationary contacts 55, 55. Flanges 56, 56 bear against washers 57, 57 which rest against the inside of the walls of the housing 50. The shanks 58, 58 of the terminals pass through holes in the walls of the housing and are fastened firmly in place by nuts 59, 59 threaded on the

shanks 58, 58. For gripping the ends of the wires to be attached to the unit, a second nut 59 is provided for each terminal 54, which nuts hold the wires between their faces and the faces of the nuts 59.

Referring to Figure 7, it can be seen that the switch blade consists of two identical portions 61, 61 which intermediate their ends have an L-shaped cross section. The vertical parts of these two L-shaped blades run unbroken substantially the full length of the blade. But the horizontal portions have a U-shaped notch cut out in the center so that each blade 61 may be slipped around the waist of the insulator 62. One blade (see Figures 6 and 7) is slipped around the waist of the insulator 62 from the left side and one from the right side. These blades 61 are connected in parallel spaced relation by the bolts 63, 63 and spacers 65, 65. The heads and nuts of these bolts rest on coiled springs 64 of the bed spring type so that the blades may be resiliently forced apart against the prestress of the springs 64, 64 when they swing into engagement with the fixed contacts 55. The spacing cylinder 66 around the shank of each of the bolts 63 lies between the blades 61 and has a length slightly less than the thickness of the contacts 55, 55 which the blades 61 engage. Each blade at each of its ends has a lateral convex contact finger 68 stamped out to form a high pressure line contact in engaging the stationary contacts 55.

It can be noted from Figures 5 and 6 that the insulator 62 has a notched central circular flange portion 67 which fits between the blades 61 and the notches of which partially surround the cylindrical spacers 65. Also, there are flanged ends 68 on the insulator 62 and a cylindrical hole 69 running through the center of the insulator through which runs the hexagonal bar 70. This bar 70 has, within the housing, a metal sleeve or shell 71 covering it. The shell 71 is cemented firmly as at 72 within the hole 69 with its longitudinal axis coinciding with that of the hole. The bar has bearing collars which are trunnioned in metal bearings cemented in the side walls of the housing 50 as at 73. When the bar 70 is inserted through the bearing collars and through the shell 71, then rotation of the bar 70 will result in rotation of the insulator and also of the blades 61 since the expanded central portion 67 of the insulator 62 will exert leverage against the cylindrical spacers 65 which are around the bolts 63. Rotating the bar 70 through an angle of 90° will disengage the blades 61 from the stationary contacts 55 and position these blades 61 in the dotted line position of Figure 6.

The housing 50 (see Figures 6 and 7) has threaded inserts 74 cemented in its back wall for screwing the unit on to the side or top of, for example, a cross arm. This prevents the housing from rotating about the bar 70 as an axle and permits the bar to rotate the switch blades 61 as above described.

A gang of three switch units 50 for three phase circuits may be mounted next to each other. Figure 2 shows such circuits and style of mounting with switch units of a different design. A single rod, such as rod 70 in Figures 5, 6 and 7, (or rod 91 in Figure 2) then passes through the whole group of rotary switches which are then operated by a single crank 89. The rod is mounted at each outer end in its own bearing brackets, such as brackets 96 of Figure 2, which

are fastened to the cross arm and which may be grounded.

The opposed lateral fingers 66 on the ends of the blades 61 are separated by a distance slightly less than the thickness of the stationary contacts 55 which they are to engage. Therefore upon rotation of the blades into engagement with the contacts 55, the blades are spread slightly against the opposing action of the prestressed springs 64. This results in positive prestressed high pressure contact between the blades 61 and contacts 55. When the blades 61 are in disengaged position they are, by design, separated from the contacts by a distance which is greater than the striking distance to metallic sleeve 71 or shaft 70 which are grounded.

Figures 2, 8 and 9 illustrate another form of rotary disconnect switch but one having the same general characteristics as the prior two. There is a wet process porcelain or glass housing 80 having a removable glass or other moulded insulation cover 81 attached thereto as by a "Bakelite" rim 83 and screws 82. Extending through the walls of opposite sides of the housing 80 are bolts 84, 84 which have at their inner ends the stationary contacts 85, 85. The nuts 86, 86 are threaded on to the threaded ends of the bolts 84 and fix the stationary contacts 85, 85 firmly in place against washers 87, 87 which separate the contacts 85, 85 from the inside of the walls of the housing 80. A second nut 88 on each bolt 84 binds the current-carrying wire (not shown) against the nut 86. The bolts 84, 84 may be cemented in place. There is provided, as in the case of the other switches, a ground connection which is closer to the contacts 85, 85 of the switch of Figures 2, 8 and 9 than the contacts are to each other.

The movable contact points 90, 90 are indirectly carried on the cylindrical rod 91 as will be described. Bearings indicated at 92 are cemented as at 93 into the side walls of the housing 80 to support the round rod 91. Each of these bearings 92 has a strap 92a (see Figure 9) extending along the outside flat wall of the housing of the unit. The strap 92a has an inturned lug 92b lying in a notch in the edge of the side wall. The lug 92b is threaded to receive the screw 82 at each side for holding the cover over the open side of the housing. The shaft 91 with its key 98 can be inserted from the side through the opening in bearing sleeve 92. The key then is brought into register with the keyway in hub member 100, as shown in Figures 8 and 9. Thin metal sleeves 92c of a thickness suitable for taking up the difference in diameters between the bearings 92 and the shaft 91 are then slipped over the adjacent ends of the shaft. Collars 92d are fastened as by set screws upon the shaft 91 at each side of the single unit or upon the shaft when the ends project from a gang of units. The sleeves 92c abut against said collars 92d at the outside and when a gang of units is placed side by side as in Figure 8, the sleeves 92c of adjacent units abut endwise against each other. Thus the movable switch members are held in register with the stationary contacts and the shaft is made to fill the stationary bearing sleeves 92. Separate from the housing and at either side of the rotary disconnect switch, or a group of them, are bearings 94 which are carried by brackets 96. The brackets 96, one for each end of the rod, are fastened by screws or bolts to a cross arm (for example see Figure 2), and may be grounded if desired. As shown in Figure 2, a single crank 89 can then operate on the one

cylindrical rod 91 and operate as many rotary switches as there are mounted in the group. Through a hole 97 in the back wall of each housing 80 (see Figure 9) extends a bolt or screw 99 which is fastened to a cross bar 96' running between and fastened to the brackets 96. This prevents the housings from revolving on the rod 91 as an axle. Bolt 99 is preferably grounded.

Keyed to the rod 91 by Woodruff key 98 is the close-fitting sleeve or hub 100 with four longitudinal ridges or keys 101 which run parallel to each other. This rod and sleeve are cemented at 102 to the inside of the waist 103 of the insulator 105. The waist 103 has a cylindrical bore but a hexagonal exterior; the insulator 105 has a generally cylindrical exterior except for the waist 103. It will now be apparent that rotation of the rod 91 will cause the insulator 105 and anything fixed to it to rotate also.

Clamped to the waist 103 of the insulator 105 is a copper braid 106. This serves both as a current conductor and as a cushion. The clamps 107 and 108 conform to the hexagonal exterior of the waist 103 but do not completely encircle it as may be seen from Figure 9. These clamps 107 and 108, clamp the copper braid 106 to the waist 103 of the insulator 105 by means of bolts 109 and 110 which run through their parallel ends. (See Figure 9.) These bolts also pass through holes in the copper braid 106 as may be seen at 111 of Figure 8.

Clamp 107 (left hand clamp of Figure 9) at each of its ends has upper and lower parallel arms 113 and 114 at one end and 115 and 116 at the other end (see Figure 8). These pairs of arms are joined by webs 117 and 118 respectively. Beyond the webs 117 and 118 the pairs of arms are still parallel but are spaced apart a greater distance and are substantially greater in width. Within the ends of these pairs of arms are rectangular slots as at 120. The two clamp and arm members are thus identical.

The movable contacts 90 are soldered to the copper braid 106 which is capable of conducting the current from one movable contact to the other around the waist 103 of the insulator 105. The braid 106 is in turn soldered to flat metal straps 121 and 122 which have turned down ends as at 123 which ends ride within and are guided by the slots 120. Optionally, pins or rivets may extend through contact 90, braid 106 and backing straps 121 and 122. A prestressed spring such as 125 keeps said straps 121 and 122, braid 106 and movable contacts 90 pressed outwardly from the center of the rotatable assembly under prestressed spring load as far as the slots 120 or an intervening object (such as the stationary contacts 85) will permit. When the movable and stationary contacts are brought into engagement, these springs, such as 124, insure smooth engagement and firm contact due to their being compressed between the webs 117 and 118 and the straps 121 and 122. These springs are held in place by a protrusion such as 127 at the center of the web 117 which fits within the coiled spring. The springs 125 are preferably but not necessarily of the bed spring type.

Optionally the fixed and movable contacts may be of the spherical high pressure type as illustrated in Figure 13. In this construction the stationary contact 85' is a button head on the bolt 84' i. e., it is spherical. Likewise, the movable contact member 90' is spherical on its engaging face. The resulting engagement is limited to a very small area, theoretically a point. Various

forms of contacts may be made such as a flat surface on the stationary contact and one or more rounded projections on the movable contact or vice versa.

The rod 91, when rotated through an angle of 90°, carries the movable contacts 90 through an angle of 90° to a position at right angles to that shown in Figure 9. This rod 91 may run through the center of a group of these rotary disconnect switches placed side by side and may be operated by a single crank as shown in Figure 2. The individual rotary switches are so constructed that when placed side by side as shown in Figure 8 they are still properly spaced laterally so as to be used without danger. Furthermore, the movable contacts 90 and braid 106 when in open position are so spaced from the stationary contacts as to afford complete safety.

Figures 10 and 11 illustrate another style of rotary disconnect switch. In design it is more like the switch of Figures 8 and 9 than the other prior forms. A glass or wet-process porcelain housing 130, has holes through its sides as at 131. (See Figure 10.) Through the center of these holes runs a hollow shaft 134 and about the shaft 134 may be placed sleeves of insulation as shown at 135, 135. If the sleeves 135 are omitted, shaft 134 may be made to serve as a connection to ground. Keyed, as at 136, to the hollow shaft 134 is a cylindrical metal hub 137 having four longitudinal ridges 138 equally spaced on its periphery and running parallel to each other. The cement 139 binds the insulator 140 to the hub 137 which is keyed to the hollow shaft 134. Consequently, if the shaft 134 is rotated in its bearings as at 133 in side plate hubs 138 then the insulator 140 and anything attached to it will rotate also.

Around the waist 142 of the insulator 140 is cemented, as at 143, an annular ring 144 which has arms 145 and 146 extending outwardly on opposite sides. At their outer ends each of these arms 145 and 146, is forked, providing fingers 147 and 148, the outer ends of which extend parallel to each other. These parallel extensions of 147 and 148 have rectangular slots 150.

Copper braid 151 for conducting the current from one movable contact 152 to the other movable contact 153 is pinned or otherwise fastened, as at 154, 154 to the annular ring 144. This conducting braid is soldered on one side to the inside surface of the movable contacts 152 and 153 and on the other side to flat metal mounting straps 155 and 156. These parts 152, 151, and 156 may optionally be fastened together by through rivets 157 as well as by solder. These mounting straps 155, 156 have their ends turned back to partially encompass coiled springs, such as 157, and also to provide offset extensions which fit into the slots 150 of the extension arms 147 and 148 where they are guided during their movement and serve to restrain the radial travel of the movable contacts.

The prestressed spring 157 tends to push the strap 156 and consequently the braid 151 and the movable contact 152 as far outwardly as the slots 150 will permit. However, when the movable and stationary contacts are engaged the movable contacts 152 and 153, the braid 151 and the straps 156 and 157 are all pushed back against the prestressed coiled spring 157 which is thereby further compressed. This assures firm contact. The form of the contacts 152 and 153 may optionally be as described above in connection with Figure 13.

The stationary contacts 159 and 160 each have threaded shanks 161, 161 which pass through

holes in the walls of the housing 130 and permit these contacts to be bolted firmly in place. These shanks also serve, in cooperation with appropriate nuts, as binding posts or terminals for the wires carrying the current (wires not shown).

The rotary disconnect switches of my invention are preferably gang operated but obviously may be segregated and individually operated. In Figure 10 left side there is indicated the edge of an adjacent rotary switch unit 165. A ring of insulation or packing 166 separates the porcelain or glass housings. At each end of the single unit or group of units the holes 131 are closed off by plates 167 (see Figure 10 and also dotted outline on Figure 11). Plate 167 has a hub 168 which fits within the eye 169 of the supporting bracket 170. The hub 168 is divided by a wall 172 into two chambers. The right hand chamber 173 of Figure 10 contains one extremity of the shaft 134. This chamber 173 is open on the side toward the observer so that a crank arm (not shown) integrally formed on the collar 174 may protrude therefrom. The collar 174 is keyed to the shaft 134. The aforementioned crank arm is fastened to usual cranking means which thereby opens or closes the switch.

A closure plate 175 closes the end of the chamber 173 and it is held in position by the tie rod 132 which extends the full length of the hollow shaft 134. This rod 132 which is anchored at the right in the flanged nut 175 extends through a similar closure plate at the other end and through a washer or flanged nut like nut 175 which is threaded or bolted on to the rod 132 at its other end. When the clamping plates 175 are drawn up tight on the threaded ends of the rod 132, all the housings of the gang switch and the side plates 167 are pressed tight against each other and are thus clamped together as a single unit. As indicated before, the shaft 134 is carried at each end in bearings 133 in the walls 172 of plates 167.

Each switch unit has its own cover such as 177 which is preferably made of glass, transparent plastic or an opaque insulating substance such as "Bakelite." A transparent cover permits the operator to see whether the switch unit is in open or shut position. To make repair of these switches easier, each cover is fastened on to one long metal bar 178 as by screws 179, 179 (see Figure 11). The bar runs parallel to the shaft 134 and rod 132 but on the outside of the housing 130. Then when the bar 178 is swung down into proper position all the covers are simultaneously swung into closed position.

To hold the bar in place so that all the housings will be held in closed position there is placed at each end of the gang of housings a locking means. This locking means consists of an arm 180, (Figures 11 and 12) pivotally mounted on a bolt extending through an ear 179 formed on each closure plate 167. The outer end of the arm 180 bears against the flat side of the end of the bar 178. Arm 180 is held tight against this strap 178 by a swingably mounted draw bolt 181 which is swung into a slot 182 (see Figure 12) and clamped therein by wing nut 184 and which is grounded.

The draw bolt 181 is itself pivoted so that it may be swung to the right (Figure 12) when the nut 184 is loosened so that the pivoted arm 180 may then be swung away from the strap 178. The draw bolt 181 at its left end (Figure 11), encircles a bolt 185 carried in flanges 186, 186. These flanges are formed integrally with the eye 169 of bracket 170. This construction permits the

movement of draw bolt 181 into and out of locking engagement.

The switch housing unit does not pivot within the eye 169 of the bracket 170 since the following rigid elements hold it in upright position: Each bracket 170 is fixed e. g., to a crossarm or upon a common base such as a piece of channel bar; its eye 169 being integrally formed is rigid; the flanges 186, 186 formed integrally on the eye 169 are rigid and carry the draw bolt 181 which is also rigid when bolted in locking engagement with the pivoted arm 180. Draw bolt 181 cannot drop into the slot 182 of arm 180 unless the arm 180 and the strap 178 beneath it are in the same vertical plane as the cross arm or mounting base on which the whole gang of units is mounted. Therefore when the covers 177 are locked on by the abovedescribed locking arrangement the units are lined up perforce vertically, with their terminals 161, 161 in vertical position.

As has been said of all the prior switches (Figures 3 through 9) the opening and closing of the switch can be accomplished in an insulating housing in the least necessary space by the rotor switch arrangement of my invention. No space-filling panels are necessary. Furthermore, the stationary and movable contacts are always pressed tightly together when in engagement with each other. A still further advantage is that these devices are inexpensive and readily assembled; their insides are easily seen and they may be opened for repairs very quickly.

Though these rotary disconnect switches are adapted to serve in conjunction with circuit breakers and to further isolate and open sections of the circuit interrupted first by the larger and more expensive circuit breakers, yet these rotary switches are adaptable for use to interrupt low current values such as normal load. When the devices shown in Figures 5 through 12 are mounted on the top of a cross arm—for they have been constructed to permit this—they may be partially filled with oil, in their bottom portions, for the housings are made of glass or wet process porcelain and will not leak. Then the making and breaking of the lower contacts will take place in the oil with the movable contact swinging out of and standing above the level of the oil.

Switches of the present type are particularly designed for power circuits of the order of 7500 volts or less and capable of carrying 200 amperes. It will be observed that in each form a double break is secured. This insures speedy interruption of any current flow and provides ample clearance. An important advantage, particularly of the forms shown in Figures 5 to 13, is the ability to space the units of a gang on the same centers as the run of conductors. So far as I am aware this is broadly new in rotary enclosed disconnect switches. Thus enclosed disconnect switches of the present rotary type may be inserted into existing runs of conductors spaced on minimum striking distances. (See, for example, runs of conductors indicated at A, B and C of Figure 2.) These switches are adapted for both indoor and for outdoor service. It will be noted that by swinging the blades in the plane of the conductors, see Figure 2, and enclosing the individual switches in housings of high insulating value, a very compact and widely useful structure is provided.

Where the spacing of the phase conductors permits or where room on the cross arm or other mounting is available, the form shown in Fig-

ures 1, 3 and 4 is highly advantageous particularly for out door service. It may here be noted too that the vertically rotatable switch elements and the stationary contacts of the devices illustrated in Figures 5 through 12 are readily adaptable for operation in a horizontal plane of rotation as used in the device of Figures 1, 3 and 4.

While I have described in detail the construction of various specific forms of my invention, it is to be understood that numerous equivalents and modifications may be employed without departing from the spirit and scope of my invention. Furthermore, I do not intend to be limited by such details of the embodiments illustrated and described above except as they are set forth and made a part of the appended claims.

I claim:

1. In a high tension disconnect switch the combination of an outer substantially enclosed housing of insulation having a circumferential wall, stationary switch contacts mounted in said housing for direct connection to line wires, a shaft disposed substantially axially of the said circumferential wall, a double ended blade lying in the plane of the contacts, an insulator mounted on said shaft and supporting said blade, a grounded element within said housing closer to one of said stationary switch contacts than the distance between said stationary switch contacts, and operating means for rocking said shaft back and forth through substantially 90° to cause the blade to engage and disengage said contacts.

2. In an electrical high tension switch, in combination, an outer substantially enclosed housing of vitreous insulation, a pair of stationary electrical terminals disposed on the inner surface of said housing, a rotatable switch member disposed within said housing for making and breaking contact at both ends thereof with said stationary contacts, a metal shaft rotatably mounted in said housing, a porcelain insulator fixed to said shaft and carrying said rotatable switch member, and a grounded element within said housing closer to one of said stationary electrical terminals than the distance between said stationary electrical terminals.

3. In combination, a gang of high tension disconnect switches each switch having an outer substantially enclosed housing of electrical insulating material and individual rotatable switch arms, the housings being arranged to provide an electrical insulating barrier between adjacent

- switches, stationary electrical contacts mounted in each housing for direct connection to line wires and a common axle extending through said housings for operating the rotatable switch arms of each of said disconnect switches simultaneously, said axle being individually insulated from said switch arms inside the housings, and a grounded element in each housing closer to one of the stationary electrical contacts therein than the distance between the stationary contacts within each of the housings.
4. In combination, a plurality of high tension disconnect switches each comprising a substantially enclosed outer housing of electrical insulating material and substantially oppositely disposed stationary electrical terminals fixed in said housing and extending thereto, said stationary terminals being of a character for direct connection with line wires, a common metal shaft extending through said housing on an axis intermediate the oppositely disposed stationary electrical terminals of each housing, a rotatable switch arm within each housing, a porcelain insulator for and carrying each switch arm, said insulators being individually keyed to said shaft for rotation therewith, and a ground closer to one of the stationary electrical terminals of each housing than the distance between the opposed stationary electrical terminals therein, said housings having wall portions forming an insulating barrier between adjacent disconnect switches.
5. In combination, a plurality of high tension disconnect switches each comprising a housing of electrical insulating material and substantially oppositely disposed electrical terminals mounted in said housing and extending thereto, said housings each being provided with a door of insulating material providing access thereto and forming a substantially enclosed chamber, a common metal shaft extending through said housings on an axis intermediate the oppositely disposed electrical terminals of each housing, a rotatable switch arm in each housing, a porcelain insulator for and carrying each switch arm, said insulators being individually keyed to said shaft for rotation therewith, and a grounded element for each switch carried by the door of each housing, said grounded element being closer to one of the electrical terminals of each switch than the distance between the opposed electrical terminals thereof.

PEDER B. HOYE.
